COMBINATION SUPPORT

Burton Wilson, San Jose, Calif.

Application February 19, 1942, Serial No. 431,581

7 Claims. (Cl. 228—2)

This invention relates to a combination support and more particularly to a combination step-ladder and lean-to scaffold support.

More particularly, it is an object of the invention to provide a support of simple construction capable of being readily converted from a step-ladder to a scaffold lean-to support, or conversely, and which when not in use can be effectively folded so that it will occupy only a very limited space.

Other objects and advantages of the invention will hereinafter become more fully apparent from the following description of the drawings, which illustrate a preferred embodiment thereof, and wherein:

Figure 1 is a side elevational view showing the support assembled as a step-ladder.

Figure 2 is a front elevational view showing the support in a folded or nested position.

Figure 3 is a side elevational view showing the support assembled as a scaffold lean-to.

Figure 4 is an elevational view taken at right angles to Figure 3 and looking toward the support from the left-hand side of Figure 3.

Figure 5 is a longitudinal sectional view taken substantially along the plane of the line 5—5 of Figure 2.

Figure 6 is a plan view, partly in sections, showing portions of the brace disconnected, and

Figure 7 is a transverse sectional view taken substantially along the plane of the line 7—7 of Figure 2.

Referring more particularly to the drawings, wherein like reference characters designate like or corresponding parts throughout the different views, 10 designates generally the support in its entirety and which includes a ladder member, designated generally 11, and a brace, designated generally 12.

The ladder member 11 includes a pair of corresponding side pieces 13 which are connected by spaced rungs 14. As best seen in Figure 1, the ends of the rungs 14 are countersunk in corresponding edges of the side pieces 13 and are connected thereto by a fastenings 15. As seen in Figure 2, the side pieces 13 converge from their lower to their upper ends.

The brace 12 includes an upper section formed by a bar 16 and a lower section, designated generally 17. The upper end of the bar 16 is disposed between the upper ends of the side pieces 13 and is provided with an opening 18 which loosely receives a bolt of a nut and bolt fastening 19. The bolt of the fastening 19 also extends through the upper ends of the side pieces 13 for 55

pivots connecting the brace 12, at its upper end, to the upper end of the ladder member 11. The lower brace section 17 includes a pair of corresponding legs 20 which are disposed in upwardly converging relationship to one another and which are connected by means of diagonal braces 21, the ends of which are countersunk in the outer edges of legs 20 and which are secured thereto by fastenings 22. The upper ends of the legs 20 are bevelled on their inner sides, as seen at 23 to rest flush against the sides of the bar 16, intermediate of its ends. Bar 16, intermediate of its ends, is provided with an opening 24 which aligns with the openings 25 in the upper ends of the legs 20 to receive the bolt of a nut and bolt fastening 26 which pivotally connects the brace section 17, at its upper end, to the intermediate portion of the bar 16. Bar 16 is provided with an opening 27, adjacent to the free end, and the legs 20 are provided with openings 28 to align therewith to receive a bolt of a nut and bolt fastening 29 for holding the brace sections, 16 and 17, in extended positions relatively to each other, as best seen in Figures 1, 2 and 5. Between the free end portion of the bar 16 and the complementary portion of the legs 20 are interposed wedge-shaped spacing members 30 through which the bolt of the fastening member 29 extends. Below the diagonal braces 21, legs 20 are braced by a cross-brace 31, the ends of which are countersunk in the outer edges of the legs 20.

From the foregoing it will be obvious that when the brace sections 16 and 17 are connected by the fastenings 26 and 29, that the brace 12 will be retained in an extended position, and may be disposed at an acute angle to the ladder member 11 to form a step-ladder, as seen in Figure 1. When the support 10 is not in use, brace 12 is swung to a folded or nested position between the side pieces 13, as seen in Figures 2, 5 and 7. Brace 12 is narrower than the ladder 11 so that when it is folded into the ladder and against the rungs 14, the outer edges of the legs 20 will not project beyond the back edges of the side pieces 13, as seen in Figures 5 and 7.

The side pieces 13 are provided with openings 32 near their lower ends and the legs 20 are provided with openings 33 adjacent to their lower ends. By removing the fastenings 29 the lower brace section can be swung relatively to the bar section 16 on the pivot formed by the fastening 26 so that the openings 33 can be aligned with the openings 32, as best seen in Figure 4, for receiving nut and bolt fastenings 34 to position the brace section 17, as seen in Figure 3. The brace section

17 is thus disposed to form a brace for the bar 16 to hold it in the position as seen in Figure 3. The free end of the bar 16 can then be rested flush against an upright surface, such as a wall, as indicated in 35 in Figure 3, so that the support 10, when assembled as in Figure 3, will form a lean-to scaffold support for an end or a portion of a platform or plank 36. It will thus be readily apparent that two or more of the supports 10, when assembled as in Figure 3, will support a platform or plank 36 to thus form a scaffold of very simple construction.

Various modifications and changes are contemplated and may obviously be resorted to, provided they fall within the spirit and scope of the invention as hereinafter defined by the appended claims, as only a preferred embodiment of the invention has been disclosed.

I claim as my invention:

1. A structure of the class described comprising a straight ladder member including upwardly converging side pieces connected by spaced rungs, a bar having one end disposed between and pivotally connected to the upper ends of the side pieces, a brace including a pair of legs pivotally connected at corresponding ends thereof to the bar, intermediate of its ends, said brace being of a length to support the bar in an approximately horizontal position when the brace is in upwardly diverging relation to the straight ladder, and means for detachably fastening the legs to the free end of the bar to hold the brace in an extended position relatively to the bar, said bar and brace, when thus arranged, being of substantially the same length as the ladder member, so that the bar and brace can be disposed at an acute angle to the ladder member, to form a step-ladder.

2. A structure as in claim 1, said fastening means being removable for positioning the brace at an angle to the bar, and means for connecting the opposite ends of the legs to the side pieces to position the bar at substantially a right angle to the ladder so that the last mentioned end of the bar can rest against an upright surface to position the support for use as a lean-to of a scaffold.
3. A structure as in claim 1, said legs being disposed in diverging relationship in a direction away from the bar.
4. A structure as in claim 1, said bar and brace being swingable into a nested position between the side pieces of the ladder.
5. A structure of the class described comprising a straight ladder member and a brace, said brace and ladder member being of substantially the same length and being pivotally connected at their upper ends, said ladder member and brace forming a stepladder, said brace being formed of sections connected in end to end relationship, said lower section being swingable relatively to the upper section to position said sections at an angle, and means for detachably connecting the lower end of the lower section to the ladder member so that the lower section will form a brace element to support the upper section at substantially a right angle to the ladder member to form a lean-to scaffold support.
6. A structure as in claim 5, said lower brace section including a pair of legs which are connected at their upper ends to the upper brace section and which diverge downwardly therefrom.
7. A structure as in claim 5, said brace being foldable into the space between the side pieces of the ladder member.

BURTON WILSON.
